UNITED STATES PATENT OFFICE.

HERBERT C. ROEDER, OF CLEVELAND, OHIO, ASSIGNOR TO AMERICAN RADIATOR COMPANY, OF CHICAGO, ILLINOIS, A CORPORATION OF NEW JERSEY.

FABRIC-CLEANING APPARATUS.

Application filed October 27, 1920. Serial No. 420,066.

To all whom it may concern:

Be it known that I, HERBERT C. ROEDER, a citizen of the United States, residing at Cleveland, in the county of Cuyahoga and State of Ohio, have invented new and useful Improvements in Fabric-Cleaning Apparatus, of which the following is a full, clear, concise, and exact description, reference being had to the accompanying drawing, forming a part of this specification.

My invention relates to improvements in means for cleaning fabrics and has particular reference to devices adapted for cleaning what is known in the art as tire liners. It is essential in using these tire liners that before they are placed in use they be thoroughly cleaned of all dust, dirt and lint. These liners vary in width and in order that the cleaning apparatus may be adapted for cleaning the varying widths of liners, I have found it advantageous and desirable to provide means for adjusting the apparatus to different widths.

For the purpose of disclosing my invention I have illustrated one embodiment thereof in the accompanying drawings.

In the drawings—

Fig. 1 is a side elevation of a cleaning apparatus embodying my invention,

Fig. 2 is a plan view thereof,

Fig. 3 is a perspective view of one of the cleaning tubes and means for adjusting it to the various widths of liners,

Fig. 4 is a sectional view of one of the cleaning tubes showing the manner of passing the fabric over the cleaning tube.

In the embodiment illustrated, upon a suitable table or bench 1 is mounted a pair of rollers 2 and 3 and these rollers are mounted at opposite ends of the bench and may be removably mounted if desired. The fabric is wound on one roll, the roll 2, and is unwound therefrom on the roll 3, a suitable driving pulley 4 being provided on the shaft of the roll for operating the roll mechanically.

Extending transversely of the bench and in the path of the fabric as it passes from one roll to the other is a cleaning apparatus. This apparatus consists as shown, of a pair of horizontally disposed transversely extending tubes 5 and 6 arranged one in front of the other and one preferably in a lower plane than the other. Each of these tubes is provided with a longitudinally extending

slot 7 in the face thereof; the slot in the tube 6 being towards the lower portion of the tube and that in the tube 5 being in the upper portion of the tube so that as the fabric is drawn between the tubes it passes under one tube and then takes a path upwardly and over the other tube. These tubes preferably take the form of pipes and are supported in position by suitable brackets or heads 8 one on each side of the bench, the brackets being held together at the top by tie rods 9 which extend through suitable bosses 10 formed on top of the brackets.

The opposite ends of the tubes are connected with branch pipes 11 each of which is closed at one end by suitable nipples or nuts 12, the opposite ends being connected to a communicating pipe 13 by suitable elbows 14. One of the branch pipes 11 is provided with a coupling 15 by which it is connected by means of a pipe 16 with a suitable vacuum producing device 17 preferably driven by an electric motor.

In the operation of the device so far described, the fabric is passed beneath one pipe and above the other and due to the connection of the vacuum producing device 17 with the two pipes air is drawn through the fabric as it passes over the slots in the pipe removing all dirt and dust from both sides of the fabric, one side of the fabric being cleaned as it passes over the lower pipe and the other side of the fabric being cleaned as it passes over the upper pipe.

In commercial use the tire liners for which this type of machine is particularly adapted vary in width and in order that the same machine may be used for operating upon the varying widths of fabric I have provided a means for adjusting the length of the slot in the tubes so that the different widths of fabric may be used.

As disclosed in Fig. 3 the tubes 5 and 6 are each provided with a sleeve 15^a. This sleeve fits snugly over the tube and will rotate thereon being held in the various rotatable positions by means of bayonet slots 16^a in the sleeve which engage a suitable pin 17^a projecting from the tube. This sleeve is provided with a longitudinally extending opening, one side 18 of which is straight from end to end and the opposite side of which is cut so that the opening varies in width. The first portion 19 of the slot is comparatively narrow, the second portion 20

is wider and the third portion 21 is still wider.

It will be noted that due to this construction portions of the slot in the tube may be closed merely by slightly rotating the sleeve. If the liner is of comparatively narrow width it will be run over the end of the tube projecting beyond the sleeve and the sleeve rotated so that the rest of the slot is entirely closed. If the liner is slightly wider than the sleeve it is rotated so that the wall 21 clears the slot in the tube and exposes a greater length of the slot for the wider tube. Likewise, if the liner is still wider the sleeve is rotated to move the wall 20 and for extremely wide liners the sleeve may be rotated so that the extreme length of the slot is exposed.

Having thus described my invention, what I claim as new and desire to secure by Letters Patent is:

1. In an apparatus of the character described, the combination with a tubular member having a longitudinal slot to form a nozzle over which fabric to be cleaned may be passed, a movable member associated with said tubular member, means on said movable member cooperating with said slot whereby, when said movable member is actuated, the effective length of said slot may be varied, and a plurality of locking devices operative upon movement of said movable member and corresponding in number with the number of positions of adjustment of said movable member whereby to locate said movable member with respect to said tubular member, and to secure said movable member in said several positions thereof.
2. In an apparatus of the character described, the combination with a tubular member having a longitudinal slot therein of uniform width to form a nozzle over which fabric to be cleaned may be passed, of a second tubular member surrounding said first-named tubular member and having a slot of varying width cooperating with the slot in said first-named tubular member to vary the effective length of the slot in said first-named tubular member, and a plurality of locking devices corresponding in number with the several widths of the slot in said second-named tubular member whereby to secure said second-named tubular member to any one of its several positions with respect to said first-named tubular member, substantially as specified.
3. In an apparatus of the character de-

scribed, the combination with a tubular member having a relatively narrow longitudinal slot therein of uniform width to form a nozzle over which fabric to be cleaned may be passed, of a second, relatively shorter tubular member surrounding said first-named tubular member and having a slot of progressively increasing width therein, and cooperating with the slot in said first-named tubular member whereby when said second-named tubular member is rotated the effective length of the slot in said first-named tubular member may be varied, and a plurality of locking devices arranged adjacent to the corresponding ends of said tubular members and corresponding in number with the several widths of the slot in said second-named tubular member whereby to secure said second-named tubular member to any one of its several positions with respect to said first-named tubular member, substantially as specified.

4. In an apparatus of the character described, the combination with a tubular member having a relatively narrow longitudinal slot of uniform width therein over which fabric to be cleaned may be passed, of a second tubular member surrounding said first-named tubular member, and having a slot therein; said slot having one of its sides straight and parallel with the longitudinal axis of said member, and its other side stepped to form a slot becoming progressively wider as it approaches one end of said second-named tubular member, and cooperating with the relatively narrow slot in said first-named tubular member whereby to vary the effective length of the slot in said first-named tubular member, a series of bayonet slots at one end of said second-named tubular member corresponding in number and position to the several widths of said slot in said second-named tubular member, and a stud on said first-named tubular member adapted to engage severally with the bayonet slots in the end of said first-named tubular member whereby to secure said second-named tubular member to any one of its several adjusted positions with respect to said first-named tubular member, substantially as specified.

In witness whereof, I have hereunto subscribed my name in the presence of two witnesses.

HERBERT C. ROEDER.
